UNITED STATES PATENT OFFICE.

WILLIAM F. SCHOWE, OF INDIANAPOLIS, INDIANA, ASSIGNOR TO SCHOWE & THOMS, OF SAME PLACE.

SAW-MILL DOG.

SPECIFICATION forming part of Letters Patent No. 291,409, dated January 1, 1884.

Application filed November 10, 1883. (No model.)

To all whom it may concern:

Be it known that I, WILLIAM F. SCHOWE, of the city of Indianapolis, county of Marion, and State of Indiana, have invented certain 5 new and useful Improvements in Saw-Mill Dogs, of which the following is a specification.

My said invention consists in a certain novel construction and arrangement of parts of that class of devices known as "saw-mill dogs" 10 for circular-saw mills, whereby such dogs may be easily and quickly adjusted, both vertically and horizontally, and quickly and securely operated.

Said invention will be first fully described, 15 and then pointed out in the claims.

Referring to the accompanying drawings, which are made a part hereof, and on which similar letters of reference indicate similar parts, Figure 1 is a side elevation of my improved dog when in operation; Fig. 2, a top or plan view thereof on an enlarged scale; Fig. 3, a longitudinal vertical section of the same on the dotted line *z z*; Fig. 4, a transverse vertical section on the dotted line *y y*; Fig. 5, an elevation of the opposite side to that shown in Fig. 1, and Fig. 6 a view looking toward the standard from the dotted line *x x*.

In said drawings, the portions marked A represent the head-block of the mill; B, the 30 standard of my improved dog; C, the vertically-sliding block; D, the handle for operating the cams in said block; E, a horizontally-sliding block; F, the dog, and G a cam-lever for operating the dog. The head-block A is 35 the ordinary head-block used in circular-saw mills, and is operated in the ordinary manner. The standard B is a straight bar of iron bolted fast to the block A, and supports the dog and its operating parts. The block C is adapted 40 to partly encircle the standard B, (see Fig. 2,) and to slide up and down thereon. It is provided with cams *c*, which are set in seats therein, (see Fig. 6,) and are provided with projecting pins *c'*, with which the cam-slots in 45 the handle D engage, whereby said cams are operated. The plate C' forms a part of the block C, and holds these cams in their seats, the pins *c'* projecting through holes in said plate, and said holes being large enough to 50 permit the necessary movement of the pins

and cams. The cams are adapted to impinge on the standard B, and thus hold the block C at any desired position thereon. The handle D is secured to the block C by a pivot-bolt, *d*. It is provided with two cam-slots, (see Fig. 5,) which engage with the pins *c'* on the cams *c*, as shown. When this handle is raised, it operates to draw the cams away from the standard B, and thus permit the block C to be moved up and down on said standard. 55 When the handle is forced down, it drives the cams tightly against the standard, and holds the block C firmly in place. The block E is mounted in ways formed therein in the side of the block C, and slides therein. It is 60 adapted to be held in any required position in said ways by the pin *e*, which passes down through a hole in one of the ways into one of a series of holes in itself. (See Fig. 3.) The dog F is secured to the block E by the pivot-bolt *f*. Its front end extends out and is adapted to enter the log, and its rear end extends back, and is formed to receive and be operated by a cam. The lever G is secured to the block E by the pivot-bolt *g*. It has a cam 75 end, *g'*, (see Figs. 1 and 4,) which fits into the correspondingly-formed portion of the dog F. When the handle end of this lever is lifted, it 80 depresses the rear and raises the forward end of the dog F, freeing said dog from the log. When it is depressed, it forces the forward end of said dog down into the log, as shown in Fig. 1, thus holding said log firmly in position.

The operation of my invention is as follows: 85 When a log is to be secured, the handle D is raised, loosening the cams, and the block C is moved up or down the standard B to the proper position. Said handle is then forced down, and, through said arms, secures the block 90 in place. The pin *e* is then raised and the block E moved in its ways along the block C until the end of the dog projects the proper distance over the log, the lever G being meantime raised. The log being turned to proper 95 position, the lever G is forced down, and the dog thus forced into the wood, securing the log, as will be readily understood by those conversant with the operation of such devices.

The standard B might be extended down be- 100

low the head-block, and another dog used to grip the under side of the log, by making such changes in the construction as are incident to turning the parts under side up, and which 5 will be apparent to any one skilled in the art.

Having thus fully described my said invention, what I claim as new, and desire to secure by Letters Patent, is—

1. The combination, in a saw-mill dog, of a 10 vertical standard, a block, C, adapted to be moved along the same, two cams, c, having projecting pins c', and a handle, D, having cam-slots which fit over and engage with said pins, whereby said cams may be operated to 15 impinge on said standard, and thus secure said block in position thereon, substantially as set forth.

2. The combination, in a saw-mill dog, of a sustaining-block, a dog centrally secured by 20 a pivot, and a cam-lever pivoted to the same block as the dog, the cam end whereof engages

with one end of said dog, and thus as said lever is raised and lowered will withdraw the dog from the log or force it into the same, substantially as set forth.

25

3. The combination, in a saw-mill dog, of the standard B, the block C, movably mounted thereon, the cams c, having projecting pins c', the handle D, provided with cam-slots, which fit over and engage with said pins, whereby said block is secured in position on the standard, the horizontal sliding block E, the dog F, mounted thereon, and the cam-lever G, for operating the same, substantially as described, and for the purposes specified.

30

In witness whereof I have hereunto set my hand and seal, at Indianapolis, Indiana, this 3d day of November, A. D. 1883.

35
